UNITED STATES PATENT OFFICE

2,327,953

SAFETY APPARATUS

Orren E. Zoder, St. Louis, Mo., assignor, by mesne assignments, to Zoder, Incorporated, St. Louis, Mo., a corporation of Missouri

Original application May 25, 1940, Serial No. 337,182, now Patent No. 2,284,709, dated June 2, 1942. Divided and this application May 15, 1942, Serial No. 443,075

4 Claims. (Cl. 287—114)

This invention relates to safety apparatus, and with regard to certain more specific features to safety apparatus for transferring hazardous fluids, such as inflammables.

The invention is a division of the invention specified in my parent application Serial No. 337,182, filed May 25, 1940, eventuated as Patent No. 2,284,709, dated June 2, 1942, which parent application is an improvement upon my Patent No. 2,212,486, issued August 20, 1940, for Safety apparatus.

Among the several objects of the invention may be noted the provision of fluid containing apparatus which has inside parts accurately adjustable from the exterior, but which is packless. Other objects will be in part obvious and in part pointed out hereinafter.

The invention accordingly comprises the elements and combinations of elements, features of construction, and arrangements of parts, which will be exemplified in the structures hereinafter described, and the scope of the application of which will be indicated in the following claims.

In the accompanying drawing, there is illustrated in longitudinal section one of various possible embodiments of the invention.

Similar reference characters indicate corresponding parts herein and in said parent application.

In the parent application certain fluid-containing transfer apparatus A is shown, a part of which is shown herein, for inflammable fluids. In chamber 5 of this apparatus is an abutment (for example, abutment 35) which is pressed by a spring 37 and requires longitudinal adjustment. This adjustment needs to be made freely from the exterior of the apparatus, without incurring leakage between adjustment periods, and without incurring the disadvantages of using packings such as leather, synthetic rubber and the like.

Numerals 7 indicates a cap threaded to the transfer apparatus to form an enclosure.

In the cap 7 is an adjustable abutment which is in the form of a cylindric adjustment plug 19 threaded into the inside of gland 21. The gland 21 is exteriorly threaded as at 23 into the threaded interior of the cap 7. The threaded opening in the cap 7 is chamfered at the bottom as shown at 25 to be engaged by the lower tapered portion 27 of the gland 21. Thus by screwing down the gland 21, the tapered portion 27 moves into the chamfer 25. This squeezes the lower edge of the taper 27 against the cylindric plug 19 so as to seal and lock it in a given ad-

justed position. The fit between 19 and the interior of 21 is close enough for the desired sealing effect. To adjust the abutment 19, the gland 21 is backed off slightly so as to remove the compressive effect above referred to, whereupon the abutment 19 may be threaded in or out to effect any desired adjustment. The threads 23 and 33 preferably have substantially the same lead so that after adjustment at 19 the tightening of 21 will not substantially change the adjustment. A screw-driver slot 29 serves the means by which the adjustment may be made of the abutment in the gland 21. This adjustable abutment it will be seen has no packing and this is considered to be novel.

To render a given adjustment tamper-proof, a wire 31 may be passed through openings 30 and this wire carries a seal 32.

Any required adjustment of spring 37 can be made by adjusting the stop 19 by use of a screw driver in the slot 29, after loosening of the gland 21. It will be seen that the clinching action at 27 around 19 after tightening of the gland is such as slightly to deform the metal of the gland into gripping relationship with the cylinder 13. This is enough to prevent leakage without the necessity for soft packing material.

In view of the above it will be seen that there is provided a very effective packless means for making the most critical interior adjustments from the outside, through a cylindric plug, with the certainty of avoiding leakage.

In view of the above, it will be seen that the several objects of the invention are achieved and other advantageous results attained.

As many changes could be made in the above constructions without departing from the scope of the invention, it is intended that all matter contained in the above description or shown in the accompanying drawing shall be interpreted as illustrative and not in a limiting sense.

I claim:

1. Adjustable abutment apparatus comprising a fluid-containing member, an opening in said member, a cylindric inner portion and a larger threaded outer portion forming parts of said opening and a tapered portion between the threaded portion and the inner cylindric portion, a gland, exterior threads on the gland cooperating with said threaded portion, a circular and completely continuous chamfered portion on the end of the gland cooperating with said tapered portion to be squeezed inward, a cylindric opening in the gland of substantially the same diameter as the cylindric inner portion of said open-

ing, a cylindric adjustment plug closely fitting said inner cylindric portion and the opening in the gland, whereby threading of the gland into the threaded portion of the opening forces the chamfer against said tapered portion to grip the adjustment plug when the gland is tightened.

2. Adjustable abutment apparatus comprising a fluid-containing member, an opening in said member, a cylindric inner portion and a larger threaded outer portion forming parts of said opening and a tapered portion between the threaded portion and the inner cylindric portion, a gland, exterior threads on the gland cooperating with said threaded portion, a circular and completely continuous chamfered portion on the end of the gland cooperating with said tapered portion to be squeezed inward, a cylindric opening in the gland of substantially the same diameter as the cylindric inner portion of said opening, a cylindric adjustment plug closely fitting said inner cylindric portion and the opening in the gland, whereby threading of the gland into the threaded portion of the opening forces the chamfer against said tapered portion to grip the adjustment plug when the gland is tightened, threads within the gland, and threads on the cylindric plug engaging therewith.

3. Adjustable abutment apparatus comprising a fluid-containing member, an opening in said member, a cylindric inner portion and a larger threaded outer portion forming parts of said opening and a tapered portion between the threaded portion and the inner cylindric portion, a gland, exterior threads on the gland cooperating with said threaded portion, a circular and completely continuous chamfered portion on the end of the gland cooperating with said tapered portion to be squeezed inward, a cylindric opening in the gland of substantially the same diameter as the cylindric inner portion of said opening, a cylindric adjustment plug closely fitting said inner cylindric portion and the opening in the gland, whereby threading of the gland into

the threaded portion of the opening forces the chamfer against said tapered portion to grip the adjustment plug when the gland is tightened, threads within the gland, and threads on the cylindric plug engaging therewith, the lead of the threads between the plug and the gland being equal to the lead of the threads between the gland and the fluid-containing member, whereby tightening of the gland may be accomplished after adjustment without affecting said adjustment.

4. Adjustable abutment apparatus comprising a fluid-containing member, an opening in said member, a cylindric inner portion and a larger threaded outer portion forming parts of said opening and a tapered portion between the threaded portion and the inner cylindric portion, a gland, exterior threads on the gland cooperating with said threaded portion, a circular and completely continuous chamfered portion on the end of the gland cooperating with said tapered portion to be squeezed inward, a cylindric opening in the gland of substantially the same diameter as the cylindric inner portion of said opening, a cylindric adjustment plug closely fitting said inner cylindric portion and the opening in the gland, whereby threading of the gland into the threaded portion of the opening forces the chamfer against said tapered portion to grip the adjustment plug when the gland is tightened, threads within the gland, and threads on the cylindric plug engaging therewith, the lead of the threads between the plug and the gland being equal to the lead of the threads between the gland and the fluid-containing member, whereby tightening of the gland may be accomplished after adjustment without affecting said adjustment, and means on the plug outside of the gland whereby it may be adjustably rotated and for holding it fixed during the period when the gland is tightened.

ORREN E. ZODER.
